(57) **CLAIM**

The ornamental design for a cut gemstone mount, as shown and described.

DESCRIPTION

The ornamental design of this patent shows a mount for a Lida cut gemstone (described in USD D543,894). The mount can be utilized for holding the gemstone on a ring, pendant, earring or broach. The shape, size, and style are specific to augment the beauty of the Lida cut gemstone and are not meant to fit or hold other traditional cuts.

FIG. 1 is a top view of my new design;

FIG. 2 is a perspective view thereof;

FIG. 3 is a long side view of my invention; the other side is a mirror image of this side; and,

FIG. 4 is a short side view of my invention; the other side is a mirror view of this side.
